UNITED STATES PATENT OFFICE.

THOMAS L. CHAPMAN, OF HUNTINGTON, WEST VIRGINIA.

TELEGRAPH-INSULATOR.

SPECIFICATION forming part of Letters Patent No. 281,452, dated July 17, 1883.

Application filed September 26, 1882. (No model.)

To all whom it may concern:

Be it known that I, T. L. CHAPMAN, of Huntington, in the county of Cabell and State of West Virginia, have invented a certain new and useful Improvement in Telegraph-Insulators; and I do hereby declare that the following is a full, clear, and exact description thereof, reference being had to the accompanying drawings, and to the letters of reference marked thereon, which form part of this specification, in which—

Figure 1 is a side elevation of my improved telegraph-insulator and its bracket. Fig. 2 is a vertical diametrical section through the same, the lower part of the bracket being broken off. Fig. 3 is a horizontal section taken in the plane indicated by dotted line *x x*, on Figs. 1 and 2.

This invention relates to insulators for telegraph-wires when the wires are sustained on poles, or by means of brackets applied to any fixed object; and the nature of my invention consists in a swivel-insulator removably applied on a bracket and constructed with a wire-slot formed by hooks, and also with a tie-groove on its periphery, as will be fully understood from the following description, when taken in connection with the annexed drawings.

Other features of my invention will be understood from what follows:

In the annexed drawings, A designates a bracket, which may be constructed in any suitable manner and adapted to be secured by bolts, spikes, or other means to a telegraph-pole, or to any other established object. On the upper end of this bracket A, I form a cylinder, B, the axis of which is vertical, and the sides of which are grooved diametrically opposite each other, as indicated at *a a*. At the base of this cylinder I form an annular groove, *b*. The top of cylinder B is flat. This cylinder is in fact a pintle or pivot, about which the insulator C is allowed to oscillate. The insulator consists of a cylinder of glass or other suitable non-conductor of electricity. It is constructed with a conetop, *c*, a central bore, lugs *d d*, which play in the annular groove *b*, and with an upright hook, *e*, and an inverted hook, *e'*. The two hooks are so formed and arranged that they leave a vertical slot, *f*, which is as broad as the said hooks. The ends of the hooks are beveled so as to form a downwardly-directed

slot, *g*, leading into the vertical slot *f*. This 55 insulator, with its double hooks, its lugs, and with a groove, *j*, in a plane near the base of the vertical slot *f*, can be readily cast entire of glass or other vitreous or non-conducting material. This swivel-insulator is applied on the cylinder or pintle B by adjusting it until the lugs *d d* will register with the vertical grooves in said pintle. These vertical grooves terminate in an annular groove above explained, so that when the insulator is at home upon 65 a shoulder of the bracket the said lugs will come within the horizontal annular groove, and the insulator will be held down in its place, although allowed to rotate about its pintle. 70

It is obvious that the insulator can be removed from its bearing or pintle by so adjusting it that the lugs *d d* are made to register with the vertical grooves in the cylindrical pintle. 75

Now, in order to apply a wire to my improved swivel-insulator, I simply pass it through the horizontal slot, and by its own tension it will fall into the vertical groove and will be there held. At certain places in the line I propose 80 to tie the wire to the insulator, using the groove above referred to, thus preventing what is known as "lost wire."

My improved insulator affords great facility for applying wires and for taking down 85 the same, especially when temporary wires are arranged in a line. It is thus obvious that I hold the wire without tying, except at a few points in the line.

Having described my invention, I claim as 90 new and desire to secure by Letters Patent—

The telegraph-wire insulator consisting of the hollow cylindro-conical body C, the lugs *d d* at the base thereof, the upturned and inverted hooks *e e'*, arranged in the same vertical plane to form a slot, *f*, and an incline passage, *g*, and the groove *j*, in combination with the bracket-pintle B, having vertical grooves *a a*, and an annular groove, *b*, all constructed and adapted to operate substantially in the 100 manner and for the purposes described.

In testimony that I claim the foregoing as my own I affix my signature in presence of two witnesses.

THOMAS L. CHAPMAN.
